Primary Examiner — Dana L Meyrow(74) *Attorney, Agent, or Firm* — Ellen Plotkin**CLAIM**

The ornamental design for a bottle, as shown and described.

DESCRIPTION

FIG. 1 is a front/side perspective view of a bottle showing my new design;

FIG. 2 is a rear/side elevational view thereof;

FIG. 3 is a front elevational view thereof;

FIG. 4 is a rear elevational view thereof;

FIG. 5 is a right side elevational view thereof;

FIG. 6 is a top plan view thereof;

FIG. 7 is a bottom plan view thereof; and,

FIG. 8 is a right side elevational view thereof.

The solid shading represents surfaces having an opaque, contrasting appearance.

The broken dot-dot-dash line in the drawings define the bounds of the claim and form no part thereof.
